UNITED STATES PATENT OFFICE.

ANDREW J. SANFORD, OF NEWARK, OHIO.

DESIGN FOR A LIGHT-SHADE.

40,260.

Specification for Design.

Patented Sept. 14, 1909.

Application filed June 21, 1909. Serial No. 503,570. Term of patent 14 years.

To all whom it may concern:

Be it known that I, ANDREW J. SANFORD, a citizen of the United States, residing at Newark, in the county of Licking and State of Ohio, have invented a new, original, and ornamental Design for Light-Shades, of which the following is a specification, reference being had to the accompanying drawing, forming a part thereof.

The drawing is a perspective view of my new design.

The leading features of my design consist in a shade body having a series of upper faces and a series of lower faces, the upper

faces being of greater flare or angle to the axis than the lower faces; and having between each pair of upper and lower faces a substantially diamond-shaped face, as shown.

The faces are provided with longitudinal prisms, as shown.

I claim:

The ornamental design for a light shade, as shown and described.

ANDREW J. SANFORD.
